DESIGN FOR A BLOUSE

Robert Ross, Brooklyn, N. Y.

Application March 19, 1934, Serial No. 51,107

Term of patent 3½ years

To all whom it may concern:

Be it known that I, ROBERT Ross, a citizen of the United States, residing at Brooklyn, in the county of Kings, city and State of New York, have invented a new, original, and ornamental Design for a Blouse, of which the following is a specification, reference being made to the accompanying drawing, forming a part thereof.

Fig. 1, is a front view of a blouse embodying my design.

I claim:

The ornamental design for a blouse substantially as shown and described.

ROBERT ROSS.
